UNITED STATES PATENT OFFICE.

HENRY J. McGUCKIN, OF NEW YORK, N. Y.

SMOKING-PIPE.

1,388,733.

Specification of Letters Patent. Patented Aug. 23, 1921.

Application filed May 28, 1920. Serial No. 384,887.

To all whom it may concern:

Be it known that I, HENRY J. McGUCKIN, a citizen of the United States, and a resident of the city of New York, borough of 5 Manhattan, in the county and State of New York, have invented a new and Improved Smoking-Pipe, of which the following is a full, clear, and exact description.

This invention relates to smoking pipes, 10 and has for an object to provide an improved construction wherein the tobacco is protected at all times and is positioned so that the smoke will readily pass out the mouthpiece.

15 Another object of the invention is to provide the round shaped bowl with an opening in line with the mouthpiece, whereby a good draft will be produced and the tobacco protected against rain.

20 In the accompanying drawings—

Figure 1 is a side view of a smoking pipe disclosing an embodiment of my invention.

Fig. 2 is a longitudinal vertical section through Fig. 1 on the line 2—2.

25 Fig. 3 is a fragmentary sectional view similar to Fig. 2, but showing a modified form of the invention.

Referring to the accompanying drawings by numerals, 1 indicates a mouthpiece 30 which is preferably round in cross section and which is fitted into the stem 2 of the pipe, it being threaded therein or held in place by friction. The stem 2 merges into a bowl section 3 which coacts with a bowl 35 section 4 to present a round or spherical structure. Section 4 is provided with an opening 5 for entrance of air and also tobacco if desired, said opening being in axial alinement with the smoke passageway in 40 stem 2.

From Fig. 2 it will be noted that the passageway 6 extends in a straight line from the end of the mouthpiece 1 to section 3 and thereby produces an easy draft especially in 45 view of the fact that the opening 5 is in alinement therewith. The sections 3 and 4 are secured together and if desired packing 7 of asbestos or other material may be used for producing a tight joint. This 50 form of bowl presents not only a pleasing appearance, but also a construction which retains the tobacco in the bowl and protects the tobacco against rain, dust or other foreign matter. Also it will be noted that 55 smoke will not readily pass from the bowl except through the passageway 6, and consequently the person using the pipe will se-

cure the advantage of receiving substantially all of the smoke through the mouthpiece 1.

In Fig. 3 a modified form of the invention is shown in which the bowl 8 is formed integral throughout. In this form of the invention the tobacco must always be passed through the opening 5, while in the form 60 shown in Fig. 2 the tobacco is usually passed through the opening 5, but if desired the sections 3 and 4 could be separated and tobacco placed in the separate sections. It will be noted that the opening 5 is comparatively small whereby the tobacco will not easily fall out even though the pipe is turned so that the opening 5 will face downwardly. In ordinary use the opening 5 and passageway 6 will be in substantially 65 a horizontal plane, though it is evident that the pipe could be smoked when arranged in any position.

The bowl is formed perfectly smooth and round inside and consequently does away 70 with the nicotin which usually accumulates in the bottom of the bowl of a pipe, the nicotin which would ordinarily form burns and passes out with the smoke. When the pipe is made in small sizes it may take the 75 place of the cigar or cigarette by reason of the smallness of the bowl of the pipe, and will use no more tobacco than will be used in the ordinary cigar or cigarette.

I claim:

1. A smoking pipe comprising a spherical bowl, a stem extending radially from said bowl formed with a smoke passageway extending in a direction radially of the center of the bowl, a mouthpiece connected with 85 said stem arranged with a smoke passageway in axial alinement with the smoke passageway in the stem.

2. A smoking pipe comprising a spherical bowl having an opening through which tobacco is adapted to be passed and a stem on the diametrically opposite side of the bowl to said opening, said stem having a smoke passageway therein extending radially with respect to the bowl, and a 100 mouthpiece connected with said stem.

3. A smoking pipe comprising an integral spherical bowl formed with an integral stem radiating therefrom, said bowl having an opening therein diametrically opposite said stem, and said stem having a smoke passageway therein in axial alinement with said opening.

HENRY J. McGUCKIN.
